UNITED STATES PATENT OFFICE.

ANDREW H. BAGGS, OF BRIDGEPORT, OHIO, ASSIGNOR TO LA BELLE
GLASS COMPANY, OF SAME PLACE.

DESIGN FOR GLASSWARE.

Specification forming part of Design No. 12,006, dated November 2, 1880.

Application filed August 4, 1880. Term of patent 3½ years.

To all whom it may concern:

Be it known that I, ANDREW H. BAGGS, of Bridgeport, in the county of Belmont and State of Ohio, have invented a new and Improved Design for Glassware; and I do hereby declare the following to be a full, clear, and exact description of the same, reference being had to the accompanying drawings, forming part of this specification, which represent a sugar-bowl, butter-dish, cream-pitcher, spoon-glass, and a casserole containing and embodying my invention.

The first element of my design consists in the combination of a belt or chain of oblong links, *a*, near the upper end of the body of the ware, plain surface below, and inclosing-bands *c c*.

A second element consists in the base, consisting of three feet made broad on their bottoms and uniting with a central piece, *e*, to form a heavy, substantial tripod-base, as shown.

A third element consists in the feet of the base, tapered from their outer end inward toward the central piece, *e*.

These last three elements are common to all the pieces of the set.

A fourth element consists in the handles *f*, shaped in the form of a double cross, each member of which is substantially rectangular in cross-section, and with or without the ornamental scroll-work *g*, being common to all the pieces excepting the butter-dish. The handle on the butter-dish cover, as well as that on the casserole, may be of double-cross form also.

A fifth element consists in the general form of the casserole—that is to say, body substantially straight at the sides and rounded at the bottom, with a tripod-base and cross-shaped handles, substantially as described.

A sixth element, and common to all, consists in the combination of a body plain at sides,

rounded at bottom, with footed base, and linked chain or band at the top.

A seventh element consists in the combination of the body, made plain at sides, rounded at bottom, with footed base, linked chain at top, and double cross-shaped handles.

To distinguish this set from others I have denominated it the "Queen Anne" set.

I claim as my invention—

1. The combination of the belt or chain, composed of oblong links, with plain surface below on the body of the ware, and with the inclosing-bands *c c*, substantially as described and shown.

2. The tripod-base consisting of the three feet made broad on their bottoms and uniting with the central base-piece, substantially as described and shown.

3. The feet of the base tapered from their outer end inward to the central base-piece, substantially as described and shown.

4. The handles shaped in the form of a double cross, each member of which is substantially rectangular in cross-section, substantially as described and shown.

5. The casserole, with body substantially straight at the sides and rounded at the bottom, with tripod-base and cross-shaped handles, substantially as described and shown.

6. The combination of the body of the ware, made plain at sides, rounded at bottom, with footed base, and linked chain or band at top, substantially as described and shown.

7. The combination of the body of the ware, made plain at sides, rounded at bottom, with footed base, linked chain or band at top, and double cross-shaped handles, substantially as described and shown.

ANDREW H. BAGGS.
